UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

NEEDLE GUARD FOR SEWING MACHINES.

Application filed September 29, 1922, Serial No. 591,232.

The invention relates to new and useful improvements in needle guards for sewing machines, and more particularly to a needle guard for a sewing machine having a thread carrying looper movable back and forth in the general direction of the line of feed. 5

An object of the invention is to provide a needle guard for a sewing machine of above type, which needle guard is mounted 10 on the work support of the sewing machine and is suspended therefrom in such a manner as to permit the looper to move over the top of the needle guard.

A further object of the invention is to 15 provide a needle guard for each needle in a multiple needle sewing machine and a common support for all of the needle guards.

These and other objects will in part be 20 obvious and will in part be hereinafter more fully disclosed.

In the drawings which show by way of illustration one embodiment of the invention—

Figure 1 is a view partly in end elevation 25 and partly in vertical section—showing a sewing machine having my improvement embodied therein;

Fig. 2 is a longitudinal sectional view on 30 the line of the needle of said machine;

Fig. 3 is a bottom plan view of the throat plate removed from the machine;

Fig. 4 is a section on the line 4—4 of 35 Fig. 3;

Fig. 5 is a section on the line 5—5 of Fig. 3;

Fig. 6 is a detail showing more or less 40 diagrammatically in side view the needle, the looper and the needle guard when the looper point is passing the needle;

Fig. 7 is a plan view of the needle, the 45 needle guard and the looper when the parts are in the same position;

Fig. 8 is an end view of the needle guards and showing relation of needles thereto.

The invention is directed to a needle 50 guard for sewing machines and more particularly to a needle guard adapted to be used in connection with a thread carrying looper which is disposed so as to move back and forth in the general direction of the line of feed and in a direction opposed to the feed when entering the needle thread loop.

My improved needle guard is carried by the work support and more particularly by 55 the throat plate mounted on the work support. Said needle guard is mounted on a bar attached to the work support or throat plate, which bar is bent downwardly so as to space the needle guard from the underside of the throat plate and provide sufficient room for the looper to move back and forth above the needle guard.

The machine to which my invention is applied is provided with a looper which not 60 only moves forward and back but also laterally during its forward and backward movement and therefore, said looper moves in a curved path. The means for operating the looper is so timed that the path of the 65 looper on its rearward movement is the same as the path of the looper on its forward movement and this curved path is so positioned that the point of the looper moves from one side of the needle to the other and thus carries the looper thread to the opposite side of the needle. The looper as it 70 is retracted is positioned so as to permit the needle to pass between the thread and the body of the looper.

The patent granted to L. Onderdonk, 75 March 2, 1920, No. 1,332,447, shows a machine having a looper which moves back and forth in the manner above described, and my improved needle guard is especially 80 adapted to be used in connection with said looper and permit the movement of the looper as specified.

The needle guard is located beneath the point of the looper as it passes the needle 85 and is so positioned as to prevent the needle from being deflected into the path of the looper.

Referring more in detail to the drawings, 90 the machine consists of a work support 1, carrying a throat plate 2. A needle 3 is mounted in a needle bar 4 which is reciprocated in the usual manner. The material is held on the work support by a presser foot 5 and is fed across the work support by a 95 feed dog 6. Co-operating with the needle beneath the work support is a thread carrying looper 7. As a matter of fact, I have shown in the drawings a sewing machine having four needles 3 and four thread 100 carrying loopers 7, one for each needle. 105

These thread carrying loopers 7 are moved back and forth in the general direction of the line of feed and the loopers move forward in a direction opposed to the feed as they enter their respective needle thread loops. The throat plate is provided with slots 8, in which the feeding section of the feed dog 6 works. The throat plate is also provided with needle openings 9, through which the needles pass. On the underside of the throat plate there is a bar 10 which is secured at 11 and 12 to the throat plate by suitable screws 13—13, the lower ends of which are shown in Fig. 3 of the drawings. The bar 10 is provided with laterally projecting lugs in which the screws 13 are threaded. The bar 10 throughout the greater portion of its length between the lugs at the ends thereof, is spaced from the throat plate, as clearly shown in Fig. 5 of the drawings. Projecting rearwardly from this bar 10 are the needle guards 14. There is, of course, one needle guard for each needle. These needle guards are located alongside of the needle opening 9, there being one guard for each needle opening. As clearly shown in Figs. 6 and 7, there is a space above the needle guards and beneath the throat plate into which the loopers move. The looper as it follows its curved path of travel crosses the needle guard and this space permits this movement of the looper relative to the needle guard. The needle guard is so positioned, that is, beneath the point of the looper when the needle enters the needle thread loop, and is on the same side of the looper as passed by the looper at this time. As a result the needle guard prevents the needle from being deflected or bent so as to be struck by the looper as it moves forward into the needle thread loop. In this particular type of machine where the looper moves back and forth in the same path and yet positions its thread on the opposite side of the needle from that passed by the looper as it enters the needle thread loop, the looper must move very close to the needle and any slight deflection of the needle is likely to bring it into the path of the looper. My improved needle guard, however, prevents this lateral deflection of the needle and insures that the looper will pass the needle without striking the same. The needle guard being supported by the throat plate provides a construction which is free from any obstructing parts beneath the work support. It also makes a very durable structure and one in which the proper position of the needle guards relative to the needles which pass through the needle openings in the throat plate may be readily obtained and maintained.

It will be noted that the needle guards are slightly curved on their upper faces to permit proper clearance for the points of

the looper, and said needle guards are cut away on their under faces adjacent the points thereof, so that the section adjacent the needle is reduced to a minimum for accomplishing the function described. 70

The needle guard is also rounded off at 14° to insure that the needle will pass the guard.

It is obvious that minor changes in the details of construction and the arrangement of the parts may be made without departing from the spirit of the invention as set forth in the appended claims. 75

Having thus described my invention, what I claim as new and desire to secure by Letters Patent, is:

1. The combination of a throat plate having slots in which feed dogs operate for feeding the material, and also having needle openings adjacent the feed slots for needles set in a line at right angles to lines passing longitudinally through the feed slots, a thread carrying looper adapted to cooperate with each needle and movable in a line longitudinally of the feed slots when entering a needle thread loop, a needle guard for each needle, said needle guards being carried by the throat plate and each located beneath the point of the looper with which it is associated when the looper is passing a needle, whereby said guard operates to prevent the needle with which it is associated from being deflected into the path of the looper with which it cooperates. 85

2. The combination of a throat plate having a plurality of feed slots formed therein, and a plurality of needle openings adjacent the feed slots and arranged in a line at right angles to lines extending longitudinally through the feed slots, a thread carrying looper adapted to cooperate with each needle and movable in a line longitudinally of the feed slots when entering a needle thread loop, a bar secured to the throat plate and extending transversely across the feed slots, said bar being spaced from the throat plate, a plurality of needle guards mounted on said bar, said needle guards being also spaced from the throat plate and each located beneath the point of the looper with which it is associated when the looper is passing a needle, whereby said guard operates to prevent the needle with which it is associated from being deflected into the path of the looper with which said needle cooperates. 100

3. The combination of a throat plate having a plurality of feed slots formed therein, and a plurality of needle openings adjacent the feed slots and arranged in a line at right angles to lines extending longitudinally through the feed slots, a thread carrying looper adapted to cooperate with each needle and movable in a line longitudinally of the feed slots when entering a needle thread loop, a bar secured to the throat plate and 105

extending transversely across the feed slots, said bar being spaced from the throat plate, a plurality of needle guards mounted on said bar, said needle guards being also spaced from the throat plate and each located beneath the point of the looper with which it is associated when the looper is passing a needle, whereby said guard operates to prevent the needle with which it is associated

from being deflected into the path of the looper with which said needle cooperates, said needle guards having their upper faces curved to provide proper clearance for the movement of the loopers.

In testimony whereof, I affix my signature.

JOHN E. CHALMAN.
